United States Patent

Des. 239,762
Patented May 4, 1976

239,762

COMPARTMENTED BOX OR SIMILAR ARTICLE

James Maurice Burden and William James Burden, both
of 319 Agostino Road, San Gabriel, Calif. 91778

Filed June 17, 1974, Ser. No. 479,799

Term of patent 14 years

Int. Cl. D9—03

U.S. Cl. D9—185

FIG. 1.

FIG. 2.

FIG. 3.

FIG. 4.

FIG. 1 is an isometric view of a compartmented box or similar article showing our new design;

FIG. 2 is a top plan view;

FIG. 3 is a side elevational view showing the side opposite that seen in FIG. 1; and

FIG. 4 is an end elevational view looking from the right of FIG. 3.

The bottom is plain and unornamented.

We claim:

The ornated design for a compartmented box or similar article, substantially as shown and described.
